CLAIM

The ornamental design for a plumbing fixture, as shown and described.

DESCRIPTION

In a preferred embodiment, the nature of this product is as a plumbing fixture in the form of a urinal for receiving the liquid waste of humans.

FIG. 1 is a left, top, front perspective view of a plumbing fixture embodying my new design;

FIG. 2 is a top plan view thereof;

FIG. 3 is a front elevational view thereof;

FIG. 4 is a left side elevational view thereof, the right side elevational view thereof being a mirror image of the left side shown;

FIG. 5 is a bottom plan view thereof; and,

FIG. 6 is a rear elevational view thereof.

The broken line representations of one or more recesses in FIGS. 1 and 3-5 and of a drain in FIGS. 1 and 2 are for the purpose of illustration only, and form no part of the claimed design.
